UNITED STATES PATENT OFFICE.

ZERA L. TANNER, OF THE UNITED STATES NAVY.

NAVIGATIONAL SOUNDING APPARATUS.

SPECIFICATION forming part of Letters Patent No. 702,507, dated June 17, 1902.

Application filed November 1, 1901. Serial No. 80,754. (No model.)

To all whom it may concern:

Be it known that I, ZERA L. TANNER, United States Navy, residing at Washington, District of Columbia, have invented certain new and 5 useful Improvements in Navigational Sounding Apparatus, of which the following is a specification, reference being had therein to the accompanying drawings.

This invention relates to machines for navi- 10 gational sounding.

The object of the invention is to produce a machine for paying out and drawing in the sounding line or wire used in navigational sounding. It is desirable that the mechanism 15 be safely incased when not in use and that none of the parts which are needful to the covering or operation of the machine shall be removable from the machine proper, although they may be displaced temporarily. For in- 20 stance, if a handle or a cover were detached and laid down on a ship's deck or in the bottom of a boat such part would be likely to be thrown about by the motion of the ship or boat and perhaps be lost overboard. I have 25 therefore devised a machine in which all the parts are connected, but in such manner that the various operating devices may be thrown into functional relation as needful. The pres- 30 ent improvement is mainly in the frame and connections.

Figure 1 is a side elevation of the machine in a closed casing with crank in operating position. Fig. 2 is an end view showing register and cranks in operative position. Fig. 3 35 is a reverse end view showing cranks disconnected. Fig. 4 is a longitudinal section of the casing and elevation of the machine, showing guiding-sheave detached. Fig. 5 is a horizontal section of the casing, showing drum 40 and gearing in plan. Fig. 6 is an enlarged vertical section of the drum, showing part of one of the cranks and showing, partly in elevation and partly in section, the brake mechanism. Fig. 7 is a broken section of parts 45 needful to show the brake. Fig. 8 is a side elevation of the device slightly modified for boat use.

The numerals 11 indicate metallic frame- 50 pieces, each of which has two legs 22, &c., which legs are held by suitable clamp-bars 33 to the base 4 in the supporting-box. The

frame-pieces are in form of spiders with a central bearing for the drum-shaft. The spiders or frame-pieces are connected by the tie-bolts 5, which support the frame against suitable 55 shoulders, as is common in machine-frames. Around the tie-bolts are sleeves 6, the ends of said sleeves being beveled. The tie-bolts and their sleeves are close to the flanges of the winding - drum, the sleeves extending 60 slightly within the periphery of the flanges, thus serving as guards to prevent the escape of the wire from between the flanges 71 of the drum 11, the spaces between the ends of the sleeves and the flanges of the drum being less 65 than the diameter of the wire.

The frame-bars 11 form bearings for the shaft 10, to which the winding-drum is rigidly attached. The shaft 10 extends outside the frame, and when the frame is inclosed in a 70 box for ship use the shaft also extends through both sides of the box.

The drum 11 is capable of containing the wire or cable *a* used for sounding. Such wire is usually a strand of perhaps one-tenth of an 75 inch in diameter. As the wire *a* is wound coil on coil—say three hundred fathoms in all—there will be a difference in the length of the outer coils from that of the inner coils. This difference is readily calculated, and a correc- 80 tion-table is generally attached to the casing, by which the error of the register may be cor- rected.

The shaft 10 has a worm 12, which engages with a shaft 14, (shaft 14 being broken away 85 in Fig. 5,) which shaft operates a register 15 outside the casing. As there is no special novelty in the register which registers the ro- tations of the shaft, and therefore the coils of line paid out from the drum, I need give 90 no special description of the register, and I do not claim the mechanism by which the register is driven. Ordinarily the register will be operated to show, approximately, the length of the wire paid out and will be re- 95 turned to zero by the winding of the line; but mechanism may be provided for return- ing the register to zero or for changing the indicator should part of the wire be lost, as is common.

In paying out the wire said wire usually runs over a sheave, as *b*, which overhangs

the ship's rail or the stern of a boat. In sounding from a boat it is generally advisable to have the register connected to sheave *b*, when the reading may be accurate. For 5 ship's use, however, I have found it better to have the register connected to the winding-drum, even though the reading be less accurate.

In permitting the wire to run out, with the 10 sounding-lead or other sounding device attached, it is generally preferable to let the drum run free from the control of the cranks by which the wire is drawn in, although the movement may be steadied by one of the 15 cranks; but to prevent too rapid movement a brake is provided, as will be explained.

The bars 17 of the frame project upward above the rim of the drum 11 and are sufficiently elastic for the purpose to be described. 20 A right-handed screw 20 is secured to one of these bars 17, and a left-handed screw 21 is secured to the other bar. These screws extend toward each other, and the threads of each screw enter a right-and-left-threaded 25 sleeve 22. A handle or hand-lever 23 is connected to sleeve 22, and by rocking this hand-lever the threaded sleeve will draw the screws out or in, and thus spring the bars 17 toward or away from the sides of the drum.

30 Brake-shoes 24 24 are secured to arms 17 in position to bear on the outer face of the drum 11. By the hand-lever 23 the drum may be held under control, even to the extent of stopping the movement of the wire. As 35 the hand-lever is in a most convenient position both for observation and operation, I consider the location above the drum to be important. The sleeve 22 lies close to and partly within the flanges 71 of drum 11 and 40 serves as a guard to prevent the escape of the wire in the same manner as sleeves 6.

While it is sometimes desirable to control the movement of the drum by the cranks, the drum is generally allowed to run free in paying out the line. The rapid rotation of a crank-handle attached to shaft 10 at such times would be inconvenient if not dangerous, while a detachable crank would be very objectionable, as the crank is liable to be 45 lost. I attach a loose sleeve 30 to each end of shaft 10. This sleeve 30 permits the shaft to rotate therein, but is held from removal from the shaft by pin 31 entering a groove in shaft 10. The crank-bar 32 is hinged to sleeve 30. 50 The crank-bar has a mortise 33, which can turn over a squared or flattened end 35 on the shaft 10. A spring-catch 36 on the crank-bar engages a notch in bar 10 to prevent the crank-bar from swinging away from the shaft 55 accidentally. The cranks are alike and can be engaged with the shaft, as in Fig. 2, so that a man at each side of the drum can secure a good operating position, or both cranks can be thrown out of clutch with the shaft 10. 60 The box 40, which contains the drum and frame, preferably stands on legs 41, which

are bolted to the deck. These legs are conveniently flanged extensions of the box ends. The box sides are notched at 43 to receive the handles 37 when the crank-handles are uncoupled from the shaft and swung down. The handles 37 enter these notches with a binding or wedging action, and the crank-bars are thus kept from swinging loose, however much the ship may pitch or roll. The 75 box-cover 46 is held by a hinge 47 to one end of the box and is fastened at the opposite end by any suitable and usual catch 49. The hinge 47 is connected to the body of the box by a swivel—that is, a bolt 50 passes through 80 that leaf of the hinge which would ordinarily be secured to the body of the box. This bolt 50 is firmly attached to the box, so that the hinge swivels around it. The box-cover can thus be swung up on its hinge and the hinge 85 swung on its pivot, so as to lie alongside the end of the box, as shown in Fig. 4. A catch or button 55 near the bottom of the box end there holds the cover, so that it cannot swing from the box no matter what the motion of 90 the ship may be.

For boat use the device is slightly modified so that the legs 2 may be secured to the top of box 60 either to the outside or inside of the box. The handles 37 when turned down 95 rest against legs 2 and are held by spring-clasps 73.

From the foregoing it will appear that the present improvement relates largely to the adjunctive mechanism by which the winding-drum is supported, protected, controlled, and operated. It may be remarked that while the drum may be of steel or iron the working parts of the reel should preferably be of bronze or some metal not subject to much 100 corrosion by the action of sea-water.

A navigational sounding apparatus must be distinguished from a ship's log in which the winding-reel is held in the hand and in which the motion of the ship or boat is compensated for by the operator, who can steady the reel by movement of his arm or person. The navigational sounding apparatus is attached to the ship or boat and partakes of the uncertain movement thereof. It is also 110 to be distinguished from deep-sea sounding apparatus which is only used when a ship or boat is at rest or comparatively so. The navigational sounding apparatus above described is too heavy and powerful to be supported by hand, yet is intended to be used while a ship or boat is moving at usual speed and even in severe weather. The wire fed out under such circumstances seldom exceeds three hundred fathoms; yet the strain 115 of drawing in a wire of this length and its attached lead generally requires the strength of at least two men. When the weather is at all rough, the difficulty of using a machine of this character is very great. My improvements are intended to overcome difficulties 120 heretofore existing in this class of machines 125 130

and are not intended to apply to hoisting-machines, brakes, cranks, or other mechanism for general purposes.

What I claim is—

5 1. In a navigational sounding apparatus, the combination with a winding-drum, of the frame supporting said drum, brake-shoes on the frame, and a hand-lever operating on the frame to compress the brake-shoes on the 10 drum.

2. In a navigational sounding apparatus, the line-supporting drum, an elastic metallic frame supporting said drum, brake-shoes on the frame at the sides of the drum, right and 15 left screws connected to the frame, and a sleeve with right and left screw-thread embracing said screws, whereby the rotation of the sleeve springs the frame and applies the brake-shoes to the drum.

20 3. The combination with the winding-drum of a machine as described, of the metallic frame having spring-bars projecting above said drum, the brake connected to said bars so as to bear on the drum, and the brake-operating lever directly above the drum, so that 25 the drum and brake are under immediate observation, substantially as described.

4. In a navigational sounding apparatus, the combination with the drum having flanges 30 as described, the wire on such drum, the frame supporting the drum, tie-bolts extending from side to side of the frame, and sleeves on the tie-bolts extending within the periphery of the drum-flanges and acting as guards 35 to the sounding-wire, substantially as described.

5. The combination, in a machine for navigational sounding, of the supporting-frame, a drum-shaft and drum carried thereby, a 40 sleeve on the shaft and free to rotate but held against longitudinal movement, a crank hinged to said sleeve, and means for engaging the crank-bar, near the hinge, with the drum-shaft, so that the crank may be operative, or turned out of the way and the drum 45 left to run free.

6. The combination, in a navigational sounding-machine, of a metallic frame, a drum and drum-shaft supported on the frame, a crank held by hinged connection to the 50 shaft, means for engaging the crank with the shaft or for permitting the shaft to run free, and a brake connected to the frame in position to operate on the drum as an auxiliary to the crank.

7. In a navigational sounding-machine, the combination with the frame, drum, and drum-shaft, of cranks having hinged connection to the shaft at each end, and means for engaging the cranks with the shaft or for turning 60 them out of working engagement, and means for holding the cranks against swinging when so turned out of working engagement with the shaft, substantially as described.

8. In a navigational sounding apparatus, 65 the combination of the frame, the drum-shaft and drum, said drum-shaft having polygonal ends, sleeves near the ends of the shaft free to turn but secured against longitudinal movement, a crank-bar hinged to each sleeve and 70 having a polygonal mortise to turn over the shaft end as described, a handle on each crank, and friction apparatus on the casing to hold the cranks when swung away from operative engagement with the shaft.

9. In a navigational sounding-machine provided with means for attachment to a ship's deck, the combination with the frame and drum, of a box inclosing the frame, the shaft extending through the box, the cranks hinged 80 to the shaft outside the box and connected by hinged connection to the shaft, said box having notches into which the crank-handles may swing to hold the cranks when not in operative engagement with the shaft.

In testimony whereof I affix my signature in presence of two witnesses.

ZERA L. TANNER.
